UNITED STATES PATENT OFFICE.

HOMER L. PHELPS, OF MARTINSBURG, WEST VIRGINIA.

CONTROLLING ATTACHMENT FOR DUMPING-WAGONS.

1,102,434.

Specification of Letters Patent.

Patented July 7, 1914.

Application filed March 27, 1912. Serial No. 686,601.

To all whom it may concern:

Be it known that I, HOMER L. PHELPS, a citizen of the United States, residing at Martinsburg, in the county of Berkeley and State of West Virginia, have invented a new and useful Controlling Attachment for Dumping-Wagons, of which the following is a specification.

This invention relates to a controlling attachment for dumping wagons whereby, through the manipulation of a single lever, the cable, chain or the like extending to the movable bottom section or sections of the wagon body may be wound, locked against unwinding, and released, at the will of the operator.

A further object is to provide mechanism of this character all parts of which are carried by a single base or attaching plate, the structure being simple and compact.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings: Figure 1 is a side elevation of the attachment and showing the lever and the other parts of the device in their initial positions during the rotation of the drum to wind the cable or chain, said drum being shown in section. Fig. 2 is a view showing the relative positions of the parts while the drum is released. Fig. 3 is a central transverse section through the attaching plate and the parts thereon. Fig. 4 is a front elevation of the attaching plate.

Referring to the figures by characters of reference 1 designates a base or attaching plate having an outstanding tubular boss 2 from which reinforcing webs 3 diverge, one of these webs terminating in an enlargement 4 constituting a bearing for a detent 5, said bearing being formed with a central outstanding boss 6 adapted to extend into an opening 7 formed in the detent.

Extending in opposite directions from the detent 5 are tongues 8 and 9 respectively, the tongue 9 being formed, preferably, with a rounded end while the tongue 8 is prefer-

ably curved and pointed as shown. Extending from one edge of the detent at a point between the tongues 8 and 9 is a nose 10, the said edge of the detent being curved from the nose to the rounded end of the tongue 9 so as thus to form a concavity, as indicated at 12. The edge of the detent is also gradually curved from the nose 10 to the point of the tongue 8, as shown at 11.

A ratchet wheel 13 is mounted for rotation on the boss 2 and its hub 14 extends around one end portion of a drum 15 or the like which preferably projects into the boss 2, the said hub being attached to the drum 15 by means of a bolt 16 extending through the hub 14 and the drum 15. A flexible element 17, such as a cable or chain is secured at one end to the drum 15 and is adapted to be wound thereon, this element constituting means for closing the movable bottom section or sections of a dumping wagon when the element is wound on the drum 15. It has not been deemed necessary to illustrate the parts to which this element 17 is attached as it can be connected thereto in any well known manner.

As shown in Fig. 1 one of the teeth of the ratchet wheel 13 is normally engaged by the nose 10 of the detent 5 and the element 17 is thus held against unwinding from the drum 15. A ring 18 is mounted for rotation on the boss 2 between plate 1 and ratchet wheel 13 and this ring constitutes one end portion of a lever 19. A pawl 20 is fulcrumed on a boss 21 outstanding from the lever 19 and has one end portion, 22, so shaped as to engage any one of the teeth of the ratchet wheel under normal conditions and as shown in Fig. 1. A curved finger 23 extends from the other end portion of the pawl and is adapted, under certain conditions, to move against the end 11 of tongue 8 as will be hereinafter described. A stop projection 24 extends from the lever below and in the path of the finger 23 and additional stop projections 25 and 26 extend from the lever 19 at points above the pawl 20. When it is desired to wind the element 17 upon the drum 15, the lever 19 is swung in the direction indicated by the arrow in Fig. 1. Pawl 20, the butt or weighted end of which normally engages the ratchet wheel 13, will thus cause the ratchet wheel and the drum to rotate with the lever, the teeth of the ratchet wheel at the same time slipping past the nose 10 of

the detent 5. When the lever is swung back to its initial position the pawl will slip over the teeth and the detent will hold the ratchet against return movement. After 5 the drum has been rotated intermittently by oscillating lever 19 until the element 17 has been wound to the desired extent upon the drum, the pawl is lifted out of engagement with the teeth of the ratchet wheel and the lever is brought to a substantially horizontal position, as indicated by dotted lines in 10 Fig. 1. When the lever moves to this position a locking stud or projection 27 which is carried by ring 18 at a point diametrically opposite lever 19, moves between the ratchet wheel and the tongue 9 and bears against the curved edge 12 of the detent, thus holding said detent positively in engagement with the ratchet wheel and locking 15 the drum against rotation in either direction. When it is desired to release the drum so as to permit the element 17 to unwind freely therefrom, lever 19 is swung in a direction opposite to that indicated by 20 the arrow in Fig. 1 until the projection 25 comes into contact with the pointed end of the tongue 8. Said projection 25 thus rides along the curved edge 11 of the detent and the tongue 8 assumes a position between the 25 two projections 25 and 26, thus locking the lever against further movement toward the detent. At the same time the nose 10 of the detent is lifted out of engagement with the teeth of the ratchet wheel and the finger 23 of the pawl moves against the edge 11 of the detent and thus lifts the butt end 22 of the pawl out of engagement with the ratchet wheel, the said finger moving 30 against the projection 24. Thus it will be seen that both the detent and the pawl are lifted out of engagement with the ratchet wheel and, by reason of the coöperation between tongue 8 and projections 25 and 26, the movement of lever 19 is stopped and the 35 detent is maintained out of contact with the ratchet wheel. The drum 15 and the ratchet wheel can thus freely rotate and the element 17 can unwind from the drum. As soon as 40 the lever 19 is swung back to its normal position, as shown in Fig. 1, the upper projection 26 swings the detent therewith during a portion of the movement of the lever, after which said detent gravitates so as to bring its nose 10 into engagement with the 45 ratchet wheel. The pawl 20 then shifts into engagement with the ratchet wheel and the operation hereinbefore described can be 50 repeated.

Importance is attached to the fact that 60 by manipulating the single lever, the flexible element can be readily wound, unwinding thereof can be positively prevented by locking the detent, and the ratchet wheel can be released from all holding and actuating means so as to rotate freely to unwind 65

the flexible element. Only a single attaching plate is necessary for carrying the various parts of the device and as there are but four of these parts it will be seen that there is practically nothing in the structure to get 70 out of order.

What is claimed is:—

1. The combination with a ratchet wheel, 75 of a lever mounted for oscillation, means for holding the wheel against rotation in one direction, means carried by the lever for actuating the wheel, and additional means carried by said lever for entering between the ratchet wheel and the holding means to lock said holding means in active position, and means carried by the lever for shifting said holding and actuating means out of active positions.

2. The combination with an attaching plate, and a bearing element outstanding therefrom, of a lever engaging and adapted to oscillate upon said element, a ratchet wheel mounted for rotation on said element, a pawl upon the lever, a detent mounted upon the attaching plate and normally engaging the ratchet wheel to hold it against rotation in one direction, means movable with the lever for entering between the detent and ratchet wheel to hold the detent in engagement with the ratchet wheel, 90 and means movable with the lever for engaging the ratchet wheel to actuate it.

3. The combination with an attaching plate, and a bearing element outstanding therefrom, of a lever engaging and adapted to oscillate upon said element, a ratchet wheel mounted for rotation on said element, a detent mounted upon the attaching plate and normally engaging the ratchet wheel to hold it against rotation in one direction, 100 means movable with the lever for entering between the wheel and one end of the detent to hold the detent in engagement with the ratchet wheel, a pawl carried by the lever and constituting means for actuating the 110 ratchet wheel, and coöperating means upon the pawl and detent for disengaging the pawl from the ratchet wheel.

4. The combination with an attaching plate, and a bearing element outstanding therefrom, of a lever engaging and adapted to oscillate upon said element, a ratchet wheel mounted for rotation on said element, a detent mounted upon the attaching plate and normally engaging the ratchet wheel to hold it against rotation in one direction, 115 means movable with the lever for entering between the ratchet wheel and the detent to hold the detent in engagement with the ratchet wheel, a pawl carried by the lever and constituting means for actuating the 120 ratchet wheel, means upon the pawl and coöperating with the detent for disengaging the pawl from the ratchet wheel, and coöperating means upon the lever and the de- 130

tent for disengaging the detent from the ratchet wheel simultaneously with the disengagement of the pawl.

5. The combination with a ratchet wheel, 5 of a detent normally engaging the ratchet wheel, a lever for rotating said ratchet wheel, and means movable with the lever and into position between the wheel and detent for binding the detent in engagement 10 with the ratchet wheel.

6. The combination with a ratchet wheel, 15 of a lever mounted for oscillation, means for holding said wheel against rotation in one direction, and separate means carried by the lever for respectively actuating the wheel, entering between the ratchet wheel

and the holding means to lock said holding means in active position, shifting said holding means and actuating means out of active positions, and co-operating with the holding 20 means to limit the movement of the lever in one direction and for imparting an initial movement to said holding means toward its active position.

In testimony that I claim the foregoing 25 as my own, I have hereto affixed my signature in the presence of two witnesses.

HOMER L. PHELPS.
